UNITED STATES PATENT OFFICE.

WILLIAM LOVELAND AND HARRY ELLWOOD SLOAN, OF PHILADELPHIA, PENNSYLVANIA.

TYPE-TURTLE OR FUDGE-BED FOR ROTARY PRINTING-PRESSES.

1,134,340.

Specification of Letters Patent.

Patented Apr. 6, 1915.

Application filed July 15, 1913. Serial No. 779,155.

To all whom it may concern:

Be it known that we, WILLIAM LOVELAND and HARRY ELLWOOD SLOAN, citizens of the United States, residing at Philadelphia, county of Philadelphia, State of Pennsylvania, have jointly invented a certain new and useful Type-Turtle or Fudge-Bed for Rotary Printing-Presses, of which the following is a specification.

10 The principal object of the present invention may be said to reside in the providing of a type-turtle or fudge-bed, so arranged, constructed and connected, that while the same is locked to place upon a printing cylinder, the different lines of type and type slugs are separately locked to the type-turtle or fudge-bed, so that if for any reason, one of the said lines of type or type slugs should become disengaged, it would 15 have no effect upon the lock-up of the other lines of type or type slugs.

20 A further object of the present invention is to provide a type-turtle or fudge-bed, designed to prevent the contents thereof dropping into the press parts, if for any 25 reason some of the lines of type or type slugs become disengaged.

25 A still further object of the present invention is to provide a type-turtle or fudge-bed, in which new and novel releasing means is provided for permitting of the withdrawal and insertion of type or type slugs.

30 A still further object of the present invention is to provide a new and novel type-turtle or fudge-bed, designed to accompany type having faces varying from 5 to 36 or more point.

35 Other and further objects of the present invention, reside in the providing of general details of construction and arrangement of parts as will hereinafter more fully appear.

40 With these and other objects in view, the invention consists of the improvements hereinafter described and finally claimed.

45 The nature, characteristic features and scope of the invention will be more fully understood from the following description, taken in connection with the accompanying drawings forming part hereof and in which:

50 Figure 1, is a top or plan view of the type-turtle or fudge-bed embodying the invention. Fig. 2, is a view in longitudinal sec-

tion taken upon the line 2—2 of Fig. 1. Fig. 3, is an end view of Fig. 2. Fig. 4, 55 is a view in cross section taken upon the line 4—4 of Fig. 2, and Fig. 5, is a fragmentary view, principally in section, illustrating the releasing device.

50 Referring to the drawings there is disclosed a physical embodiment of the invention constructed in a manner best known to us at this time for practicing the invention.

60 The type-turtle or fudge-bed is shown as having a relatively thick one piece bed 65 plate 10, which is segmental in form. Formed integral with the bed plate and projected upwardly therefrom are a multiplicity of relatively thin elongated ribs 11. These ribs are segmental in form and are 70 closely adjacent one another to form continuous grooves 12, for receiving the webs or shanks 13 of type 14. Upon each side of the type-turtle a removable plate *a*, completes the series of grooves 12. These plates 75 *a*, are secured by means of screws *b*, to the base and end plate 16 about to be described. Detachably secured to one end of the bed plate 10, as by screws 15, is an end piece 16, which is segmental in form and which 80 is provided preferably adjacent its top with a multiplicity of apertures 17 arranged upon an arc of a circle, see Fig. 4, there being one aperture in alinement with each of the grooves 12. Each aperture 17, accom- 85 modates a fixed pointed pin 18, see Fig. 2. As clearly shown in said figure, the pins are provided with an enlarged head, and a contracted shank, and the apertures 17 are so formed to accommodate such construction. 90

95 The opposite end of the bed plate 10, is also provided with a removable end piece 19, secured as by screws 20. This end piece 19, is also segmental in form, and is apertured for the passage therethrough of shift- 95 able pointed pins 21. These pins 21, are somewhat larger than the pins 18, and it is necessary to arrange them in staggered relation adjacent the top of the end piece 19, as shown in Fig. 3. These shiftable pins 21, 100 are provided with enlarged heads and contracted shanks, and between the heads thereof, and the outer wall of the end piece 19, are interposed coiled springs 22. A shiftable head 23, normally in abutting position, 105 with the end piece 19, is present, and the

shanks of the pins 21 are fixed with respect to said head by means of screws 24. The pins 21, by virtue of the springs 22, are normally held in position shown in Figs. 1 and 5 2, for engagement with the webs or shanks 13 of the type 14, it being understood that one pin 21 is present opposite each of the grooves 12. By moving to the left in Figs. 1 and 2, the head 23, the pins 21, may be 10 caused to be shifted away from the grooves 12, as clearly shown in Fig. 5, so that one or more of the lines of type or type slugs may be withdrawn or placed within the type-turtle or fudge-bed. For convenience in 15 shifting the head 23, we have designed a tool to readily accomplish this result. As shown in Fig. 5, this tool comprises a handle 25, having a foot 26, for engagement with the end of the base plate 10, and further having a finger piece 27, terminating in 20 journals 28 adapted to engage sockets 29, fixed to the head 23. With the tool in the position shown in Fig. 5, the head may be readily moved to the position shown and 25 the pivotal detent 30 is then dropped to a position between the head 23, and the outer wall of the end piece 19 to retain the head in shifted position. Obviously by lifting the 30 detent 30, the resiliently held pins 21, return to operative position.

By the above described arrangement and construction of parts, a type-turtle or fudge-bed is provided in which each line of type has its own separable distinct lock-up and if 35 for any reason one line of type should become disengaged, it would have no effect on the lock-up, or any of the other lines of type. Consequently the disadvantage of having the contents of the type-turtle dropping into 40 the press parts is obviated.

Another advantage resides in the fact that with one operation, all of the lines of type or type slugs are simultaneously locked to place and likewise with one operation, all 45 of the lines of type may be released.

By the particular formation of the strips 11, and grooves 12, various sizes of type faces may be employed, for instance sizes from 5 to 36 or more point. In this connection it will be understood that the upper surface of the strips 11, support the overhang 31, of the larger size of type. It may be here remarked that in practice, it is customary to fill the grooves 12, not occupied, 50 by type with type slugs, in order that all of the pins 18 and 21 may be embedded within webs or shanks, in order to provide general rigidity. In the drawings however, the type slugs have been omitted for the sake 55 of clearness.

What we claim is:

1. In a type-turtle or fudge-bed, a segmental bed plate, a series of elongated closely adjacent, segmental strips fixed to 60 the bed plate to form continuous type re-

ceiving grooves, end pieces fixed to the bed plate of which one end piece is provided with fixed pins and of which the other end piece is apertured, for the passage therethrough of shiftable resiliently held pins, 70 each set of pins being alined with aforesaid grooves and means for moving the shiftable pins away from said grooves to permit of the withdrawal and insertion of type.

2. In a type-turtle or fudge-bed, a bed 75 plate segmental in form having formed integral therewith a series of elongated, closely adjacent, equally spaced segmental strips, forming continuous type receiving grooves, end pieces removably fixed to the respective 80 bed plate ends, of which one end piece is provided with fixed pins and of which the other piece is apertured for the movement therethrough of resiliently held pins, each set of pins being in alinement with the 85 aforesaid grooves, and a head operatively connected with the movable pins for shifting them in unison away from said grooves to permit of the withdrawal and insertion of type. 90

3. In a type-turtle or fudge-bed, a bed plate segmental in form, having formed integral therewith a series of elongated, alined, equally spaced, segmental strips, forming continuous type receiving grooves, end 95 pieces removably fixed to the bed plate immediately adjacent the strip ends of which one end piece is provided with fixed pins, arranged upon an arc of a circle, and of which the other end piece is apertured for 100 the passage therethrough of shiftable resiliently held pins, arranged in staggered relation upon arcs or circles, all of said pins being disposed in alinement with the aforesaid grooves, and a head operatively connected with the shiftable pins for moving them away from said grooves. 105

4. In a type-turtle or fudge-bed, a segmental bed plate, a series of elongated closely adjacent, segmental strips having 110 fixed relation with the bed plate to form continuous type receiving grooves, end pieces fixed to the bed plate of which one end piece is provided with fixed type engaging means and of which the other end 115 piece is apertured for the passage therethrough of a multiplicity of longitudinally disposed resiliently held mediums spaced apart in juxtaposition to one another and extended across the entire width of the type 120 turtle or fudge bed, the working ends of which are designed for independent type slug engagement and means operatively connected with said mediums for shiftable purposes. 125

5. A type-turtle or fudge-bed embracing a bed plate constructed for type slug reception, end pieces for the bed plate of which one is provided with fixed type slug engaging means and of which the other end 130

piece is constructed to shiftably accommodate a multiplicity of resiliently held mediums spaced apart in juxtaposition to one another and extended across the entire width
5 of the type-turtle or fudge-bed the working ends of which are designed for independent type slug engagement.

In testimony whereof, we have hereunto signed our names.

WILLIAM LOVELAND.

HARRY ELLWOOD SLOAN.
